SCRAPER DEVICE FOR CONVEYERS

Filed March 19, 1928

UNITED STATES PATENT OFFICE.

JOSEPH F. NOECKER, OF BLOOMFIELD, NEBRASKA.

SCRAPER DEVICE FOR CONVEYERS.

Application filed March 19, 1928. Serial No. 262,829.

This invention relates to conveyers of that type to be used in construction work on roads, in building tunnels, etc., and has for its object to provide, in a manner as hereinafter set forth, a conveyer of the class referred to with a new and improved scraper means positioned at the lower or material receiving end of the belt or elevator of the conveyer, to prevent mud and dirt from 10 lodging on the inside thereof and adhering to the roller for the belt, and further for cleaning any adhering dirt from the roller during the revolving thereof, whereby the conveyer will not become clogged and its 15 operation retarded.

Further objects of the invention are to provide, in a manner hereinafter set forth, a scraping element and its support for use in connection with a conveyer of the class 20 referred to and for the purpose aforesaid, and whereby said scraper element and its support is comparatively simple in its construction and arrangement, strong, durable, compact, thoroughly efficient in its use, 25 readily installed with respect to the lower or material receiving end of the conveyer, and comparatively inexpensive to set up.

With the foregoing and other objects in view the invention consists of the novel construction, combination and arrangement of parts as hereinafter more specifically described, and illustrated in the accompanying drawings, wherein is shown an embodiment of the invention, but it is to be understood 35 that changes, variations and modifications can be resorted to which fall within the scope of the claims hereunto appended.

In the drawings wherein like reference characters denote corresponding parts 40 throughout the several views:—

Figure 1 is a fragmentary view in longitudinal section of the lower or receiving end of a conveyer showing the adaptation therewith of a scraping element and its support 45 in accordance with this invention.

Figure 2 is a fragmentary view in plan illustrating the scraper element and its support.

Figure 3 is a fragmentary view in elevation looking toward the inner side of the

scraper element and further illustrating one of the supporting members therefor.

Figure 4 is a cross sectional view illustrating the lower roller of the belt and the scraper element in accordance with this invention arranged in set position with respect to the roller. 55

Figure 5 is a fragmentary view in longitudinal section of the scraper element and further illustrating one of the supporting 60 members therefor.

Referring to the drawings in detail 1 and 2 indicate a pair of adjustable supporting plates arranged at the lower or receiving 65 end of the conveyer. As is well known

and as shown in my application Serial Number 147,061 the said supporting plates are carried or mounted upon foot blocks arranged in spaced parallel relation and positioned below the receiving end of the conveyer. 70

With reference to Figure 1 one of the side bars of the conveyer body is indicated at 3, one of the dirt guards at 4, one of the side plates at 5 which projects 75

beyond the lower end of the conveyer body and is connected to the dirt guard 4. The lower roller for the belt or elevator 7 is indicated at 8 and is mounted in bearings 9

formed on the plates 1, 2. The elements 3 to 8 are of known construction and form 80 no part of the invention forming the subject matter of this application. The elements 3 to 8 are illustrated for the purpose of

showing the adaptation of the scraper element and its supporting means, in accordance with this invention, with respect to the lower or receiving end of the conveyer. The elements 3 to 8 are constructively referred 85

to in my application 147,061 and it is thought unnecessary to specifically describe the arrangement and function thereof in this application. 90

The adjustable supporting plate 1, as well as the plate 2 comprises a forward and a rear portion 10, 11 respectively and with 95 the former of less width than the latter. The bearings 9 are carried by the forward portions 10 of the plates 1 and 2 and project from each side edge thereof. The roller 8 has reduced end portions 12 which extend 100

into the bearings 9. The forward portions 10 of the plates 1, 2 are provided with slots 13. The rear portion 11 of the plate 1, as well as the rear portion 11 of the plate 2, is formed with a pair of spaced slots 15 disposed lengthwise thereof. The outer side of each rear portion 11, intermediate its ends is formed with an integral up-standing apertured lug 16. The rear end of each portion 11 is formed with an up-standing apertured lug 17. Each lug 17 has coacting therewith an adjusting screw 18. The lugs 16, 17 and screws 18 function for the same purpose as that set forth in my application Serial Number 147,061 and form no part of the invention of this application.

A scraper element in accordance with this invention comprises a one-piece body portion 19 of arcuate curvature in vertical section and conforming in curvature to that of the roller 8. The body portion 19 is concave and is positioned inwardly of and in close proximity to the roller 8. The body portion 19 is of uniform width throughout and of such width whereby it will extend upon the top and bottom of the roller 8. See Figures 1, 2 and 4. The body portion 19 is of slightly less length than the length of the roller 8. The body portion 19 at its top and bottom is provided with a scraper edge as indicated at 20, 21 respectively. Disposed at the longitudinal median of the rear face of the body portion 19 are integral rearwardly extending spaced lugs arranged in pairs and with the lugs of one pair indicated at 22 and the lugs of the other pair at 23. The lugs of each pair are arranged in opposed spaced relation and the outer lug of each pair is positioned in proximity to and end of the body portion 19. Each lug of each pair is provided with an opening 24 disposed in alignment with the longitudinal median of the body portion 19. Each lug of each pair is further formed with a rearwardly directed opening 25 having a threaded wall and which communicates with the opening 24 approximately centrally thereof. Threadedly engaging with the wall of each opening 25 is a rearwardly directed binding screw 26.

Associated with each end of the body portion 19 is means for suspendingly supporting the scraper element in active position 55 with respect to the roller 8 and said means is bodily adjusted for the purpose of adjustably positioning the scraper element 20 with respect to the roller 8. The means associated with each end of the scraper element for suspendingly supporting it consists of a bar 27 for extension through a pair of lugs 22 and which is fixedly secured to the lugs by the set or binding screws 26. The outer end of the bar 27 is integral with the upper face of the enlarged

outer end 28 of a flat plate 29 provided with a pair of spaced lengthwise extending slots 30 for registration with the slots 15, in a plate 1 or 2. The plate 29 is positioned upon the upper face of the rear portion 11 of the plate 1 or 2 and is adjustably connected thereto by vertically disposed bolts 31 carrying clamping nuts 32. The bolts 31 extend up through the registering slots 15, 30 and the nuts 32 engage the upper faces of the plates 29 whereby the supporting means for the scraper element is fixedly secured in its adjusted position.

It is thought the many advantages of a so scraper element and its support, in accordance with this invention, can be readily understood, and although the preferred embodiment of the invention is as illustrated and described, yet it is to be understood that changes in the details of construction can be had which fall within the scope of the invention as claimed.

What I claim is:

1. A scraping means for the lower roller 90 of an endless conveyer or belt comprising a one-piece scraper element of arcuate transverse cross section having a scraping edge at each side thereof to oppose the top and bottom of the roller with which it is associated, apertured lugs projecting rearwardly from said element near each end thereof and between said edges, an adjustable support for each end of said element extending through said lugs, and means for 95 fixedly securing the supports to said element.

2. A scraping means for the lower roller 105 of an endless conveyer or belt comprising a one-piece, concave scraper element upon 105 the same arc throughout in transverse section, a support for each end of said element positioned rearwardly thereof, means for fixedly securing the supports to said element at the rear of each end of the latter, and means to provide for the adjustment of said supports and for fixing them in adjusted position.

3. A scraping means for the lower roller 115 of an endless conveyer or belt comprising a 115 one-piece scraper element of arcuate transverse section, said element being of uniform width and concave to overlie the top and bottom of the roller with which it is associated, a support for each end of said element, said supports arranged rearwardly of said element and each having a part thereof opposing the longitudinal median of the element at the rear thereof, means for detachably connecting said parts to said 120 element at the rear thereof, and means for adjustably securing said supports in position.

4. A scraping means for the lower roller 130 of an endless conveyer or belt comprising

- a one-piece scraper element of arcuate cross section and of uniform width, positioned on a lengthwise edge and having a scraping edge at each side thereof, a pair of adjustable supports, each of said supports including a base part arranged rearwardly of and at right angles to said element and a forward part disposed at right angles to the base part and opposing the longitudinal
- 5 said element near each end of the latter and arranged between said scraping edges, means disposed parallel with the rear of said element and extending through said coupling means for suspending the element, and adjustable supporting plates disposed rearwardly of and at right angles to said element and having said last mentioned means integral with the outer ends thereof.
- 10 median of said element, and means for detachably connecting said forward part to said element.
- 15 5. A scraping means for the lower roller of an endless conveyer or belt comprising a one-piece, concave scraper element upon the same arc throughout in transverse section, apertured means integral with and projecting rearwardly from said element near each end of the latter, and adjustable means arranged
- 20 rearwardly of said element and having inwardly projecting, right angularly disposed parts extending through and secured to said apertured means and providing a supporting structure for suspending said element.
- 25 6. A scraping means for the lower roller of an endless conveyer or belt comprising a one-piece, concave scraper element upon the same arc throughout in transverse cross section and having a scraping edge at each side
- 30 thereof, and said element being further provided with spaced means projecting rearwardly therefrom near each end thereof for connection to a suspension means for said element.
- 35 7. A scraping means for the lower roller of an endless conveyer or belt comprising a one-piece scraper element of concave transverse cross section for disposing lengthwise thereof with respect to the rear of the roller
- 40 and of a width to oppose the top and bottom of the roller, and means secured to the rear of said element at each end of the latter to provide a supporting structure therefor to suspend the element with respect to the
- 45 roller.
8. A scraping means for the lower roller of an endless conveyer or belt comprising a one-piece scraper element of uniform width and of concave transverse cross section for
- 50 positioning lengthwise of the rear of the roller, and adjustable means detachably connected in said element between its upper and lower edge at each end thereof for suspendingly supporting it in active position with
- 55 respect to the roller.
9. A scraping means for the lower roller of an endless conveyer or belt comprising a one-piece scraper element of concave cross section having a scraping edge at each side
- 60 thereof, said element conforming in curvature to that of the roller and having its scraping edges disposed for positioning upon the rear of the top and bottom of the roller, adjustable coupling means integral with and
- 65 projecting rearwardly from the rear face of
- 80
- 85
- 90
- 95
- 100
- 105
- 110
- 115
- 120
- 125
- 130

In testimony whereof, I affix my signature hereto.

JOSEPH F. NOECKER.
